UNITED STATES PATENT OFFICE.

EDWARD JAMES, OF CLEVELAND, OHIO.

THREAD-PROTECTOR.

1,361,525.

Specification of Letters Patent. Patented Dec. 7, 1920.

Application filed April 28, 1915, Serial No. 24,472. Renewed July 12, 1919. Serial No. 310,501.

To all whom it may concern:

Be it known that I, EDWARD JAMES, a citizen of the United States, and a resident of Cleveland, county of Cuyahoga, and State of Ohio, have invented a new and useful Improvement in Thread-Protectors, of which the following is a specification, the principle of the invention being herein explained and the best mode in which I have contemplated applying that principle, so as to distinguish it from other inventions.

The desirability is well understood of protecting the thread on the ends of pipe or like articles which are generally threaded at the manufacturing plant where such pipe is made; for, unless thus protected, the thread is apt to become battered or otherwise damaged in the course of shipment, and while the pipe is lying around in the yard or field, and so necessitate partial re-threading before such pipe can be used. The present invention has as its object the provision of a protector of this sort which will not only be so inexpensive as to render its use commercially feasible, but which may be readily applied and equally readily removed, while still remaining securely affixed to the pipe at all times when desired that the thread should be protected. To the accomplishment of the foregoing and related ends, the invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:-

Figure 1, is a central vertical section of one form of my improved thread protector before being applied; Fig. 2 is a central vertical section of the same together with the threaded end of a pipe onto which such protector has been applied; Fig. 3 is a front elevational view of one component element of the protector; Fig. 4 is a view similar to Fig. 1 but illustrating certain modifications in construction; Fig. 5 illustrates another modification in one of the component elements of the device; and Figs. 6 and 7 respectively illustrate still other modifications in the same element.

Referring first of all to the form of construction illustrated in Figs. 1 and 2, the

device will be seen to comprise two principal elements, viz., a helically coiled wire 1 and a stamped metal cap 2 fitted over one end of such wire coil. The internal diameter of the latter should preferably be a trifle less than the external diameter of the threaded portion of the pipe 3, onto which the device is designed to be fitted when in use, and the internal diameter of the cylindrical portion of the cap is such as to easily slip onto the corresponding end of the coil in the normal condition of the latter before it has been thus applied to the pipe-end.

In order to apply the device, the projecting portion of the coil is started on the thread, and by rotation in the proper direction the entire coil, or practically the entire coil, is in effect screwed onto such end. The effect of this operation is to tend to spread the portion of the coil that lies within the cap so as to firmly grip the cylindrical wall of the latter, this action being due both to the expanding effect on the portion of the coil in question produced by screwing the other portion thereof onto the pipe thread, and by the taper of such thread itself.

The terminal convolution 4 of that end of the coil which is received in the cap is desirably bent inwardly so as to be of smaller diameter than the main body of the coil, and a section 5 thereof bent still more sharply so as to lie transversely of the body of the coil as best shown in Fig. 3. This terminal convolution, with the transversely disposed end of the wire, not only serves as a stop to limit the longitudinal movement of the coil in screwing the same on the pipe end, but also provides means, should the cap be removed before the coil, for rotating the latter or pulling it bodily free from the pipe end. It is contemplated, however, that ordinarily it will be sufficient, in order to remove the device, to simply rotate the cap in the proper direction to unscrew the coil, whereupon the cap may be readily freed from the coil and the coil from the pipe end.

As illustrated in Figs. 1, 2 and 3 of the drawing, the wire of which the coil is composed is of substantially circular cross-section. It will of course be understood that such wire may be of polygonal, for example of triangular cross-section, as shown in the wire 7 in Fig. 4, moreover, I show a modified form of cap 8, in that the latter is of annular instead of closed form, the central aperture 9 therein permitting of access

to the interior of the pipe as may be desirable where it is desired to enamel the latter, or otherwise coat the interior thereof, as is necessary in order to prepare the pipe 5 for certain uses. The thread of course is equally effectively protected whether the cap be thus annular or closed.

In order still more firmly to secure the cap in place when the coil has been threaded 10 onto the pipe end, such cap, instead of being left with its interior surface perfectly smooth, may have one or more projections 10 stamped up or otherwise formed in such wall, as illustrated in the case of cap 11, 15 Fig. 6, to engage or interlock with the convolutions of the coil. A further modification in the construction of the cap is shown in the cap 12 of Fig. 5, such modification consisting in making the open end thereof of 20 smaller diameter than the closed end, so that the side walls flare as indicated. This form of side wall permits the terminal convolutions of the coil to expand to a larger diameter than would otherwise be the case, and 25 the more firmly secures the cap in place on the coil. In order to permit of the ready removal of the cap in such case, one or more slits 13 will desirably be cut in the side wall thereof as shown. The cap may thus be 30 simply sprung off of the coil, and the latter unscrewed, as it were, by rotating the same through the medium of the transversely disposed end-section 5 provided for the purpose, or otherwise as found most convenient. 35 When it is desired to employ a single helical coil, without having its terminal convolution formed as illustrated in Fig. 3, it will be desirable to form the cap specially, as illustrated in Fig. 7, so that it will rotatably 40 engage the end of such convolution. Thus the cap 14 illustrated in Fig. 7 is provided with a lug 15 projecting inwardly from the side wall adjacent such cap's closed end, which lug is adapted to abut against the 45 end of the convolution 16, when the cap is rotated in the direction indicated by the arrow. Such rotation will obviously have a positive effect to unwind the coil from the threaded pipe end, thus assisting the tendency due to the mere frictional engagement 50 of the coil with the cap.

Other modes of applying the principle of my invention may be employed instead of the one explained, change being made as 55 regards the mechanism herein disclosed, provided the means stated by any of the following claims or the equivalent of such stated means be employed.

I therefore particularly point out and distinctly claim as my invention:—

1. In a device of the character described, the combination with a helical wire coil adapted to screw onto a thread; of a casing 60 normally fitting said coil so as to be readily removable therefrom, said coil being ex-

panded to interiorly grip said casing when thus screwed onto a thread.

2. In a device of the character described, the combination with a helical wire coil adapted to screw onto a thread; of a casing 70 normally fitting said coil so as to be readily removable therefrom, said coil being expanded to interiorly grip said casing when thus screwed onto a thread, the side wall of said casing being fashioned to positively interlock with said coil in the latter's expanded condition.

3. In a device of the character described, the combination with a helical wire coil adapted to screw onto a thread; of a casing 80 normally fitting said coil so as to be readily removable therefrom, said coil being expanded to interiorly grip said casing when thus screwed onto a thread, the side wall of said casing being of smaller diameter 85 at its open than at its closed end so as to positively interlock with said coil in the latter's expanded condition.

4. In a device of the character described, the combination with a helical wire coil 90 adapted to screw onto a thread; of a casing normally fitting said coil so as to be readily removable therefrom, said coil being expanded to interiorly grip said casing when thus screwed onto a thread, the side wall 95 of said casing being of smaller diameter at its open than at its closed end so as to positively interlock with said coil in the latter's expanded condition and such side wall being slit to permit of its forceful removal from 100 said coil.

5. In a device of the character described, the combination with a helical wire coil adapted to screw onto a thread; of a casing 105 normally fitting said coil so as to be readily removable therefrom, said coil being expanded to interiorly grip said casing when thus screwed onto a thread and having its terminal convolution within said casing bent transversely with respect to the body of the 110 coil.

6. As an article of manufacture, a helical wire coil adapted to screw on a thread to protect the same, said coil having one terminal convolution bent transversely with 115 respect to the body of the coil and adapted to rest upon the end of the threaded article, substantially as and for the purpose described.

7. As an article of manufacture, a helical 120 wire coil adapted to screw on a thread to protect the same, said coil having one terminal convolution of smaller diameter than the body of the coil and its extremity bent transversely with respect to the latter and 125 adapted to rest upon the end of the threaded article substantially as and for the purpose described.

8. In a device of the character described, the combination with a cylindrical casing 130

open at one end, of a spring fitted therein and engaging the same laterally, said spring being longer than said casing and being adapted to engage a threaded pipe end or 5 the like, substantially as described.

9. In a device of the character described, the combination with a cylindrical casing open at one end, of a spring fitted therein and engaging the same laterally, said spring 10 being adapted to engage a threaded pipe end, said pipe end being adapted to spread said spring sufficiently to make a tight frictional engagement between said spring and said casing.

15 10. A thread protector, comprising a casing having a substantially circular locking member therein conforming to the circumferential configuration of the threads of a pipe or the like, said member being radially yielding whereby it will be spread radially 20 against the casing by the pipe and be brought into frictional engagement therewith and thereby be forcibly held in frictional engagement with the threads throughout 25 out substantially the entire circumference of such threads.

11. A thread protector comprising a substantially cylindrical casing, a yielding locking member engaged by and rotatable with

said casing, said locking member conforming to and frictionally engageable with the pipe or the like circumferentially throughout several radians and free for expansion and contraction throughout with respect thereto, said locking member also having a 30 yielding and advanced portion for engagement with the pipe whereby relative rotation causes the locking member either to lessen its frictional hold upon the pipe to facilitate application or to grip the pipe to resist 35 removal.

12. A thread protector, comprising a casing having a cylindrical interior, a locking member therein conforming to the circumferential configuration of the threads of a 40 pipe or the like, said member being radially yielding whereby it will spread against the casing by the pipe and be brought into frictional engagement therewith and thereby be forcibly held in frictional engagement with 45 the threads throughout substantially the entire circumference of such threads.

Signed by me, this 26th day of April 1915.

EDWARD JAMES.
